Primary Examiner — Messina L Smith
Assistant Examiner — Elizabeth Borsetti(57) **CLAIM**

The ornamental design for a mini hair straightener, as shown and described.

DESCRIPTION

FIG. 1 is a perspective view of a mini hair straightener showing my new design;

FIG. 2 is an enlarged front elevational view thereof;

FIG. 3 is an enlarged rear elevational view thereof;

FIG. 4 is a left side elevational view thereof;

FIG. 5 is a right side elevational view thereof;

FIG. 6 is an enlarged top plan view thereof; and,

FIG. 7 is an enlarged bottom plan view thereof.

The broken lines in the drawings depict portions of the mini hair straightener that form no part of the claimed design.
